MEANS FOR TREATING ASPHALT

Joseph Adelbert Withee, Kansas City, Mo., assignor of one-half to Garde J. Hines, Kansas City, Mo.

Application August 18, 1933, Serial No. 635,734

15 Claims. (Cl. 94—43)

The device forming the subject matter of this application embodies novel means for tempering asphalt rock and petroleum asphalt, and for fusing them with a binder, to make a superior grade 5 of mica asphalt, fuel being saved, the period of operation being cut down, and continuously acting means being supplied for delivering the material and for carrying away the finished product.

It is within the province of the disclosure to 10 improve generally and to enhance the utility of devices of that type to which the invention appertains.

With the above and other objects in view, which 15 will appear as the description proceeds, the invention resides in the combination and arrangement of parts and in the details of construction hereinafter described and claimed, it being understood that changes in the precise embodiment of the invention herein disclosed, may be made 20 within the scope of what is claimed, without departing from the spirit of the invention.

In the accompanying drawings:

Fig. 1 shows in vertical longitudinal section, a 25 device constructed in accordance with the invention, parts being in elevation;

Fig. 2 is an end elevation, wherein parts are in 30 section;

Fig. 3 is a cross section on the line 3—3 of Fig. 1;

Fig. 4 is a transverse section through the pipe 35 which connects the drums.

In carrying out the invention, there is provided an arched casing 1, which may be made of brick work. The casing 1 includes a front transverse base wall 2 and a rear transverse base wall 3, as 40 shown in Fig. 1. The base wall 2 is set inwardly a little from the forward end of the casing 1. The casing 1 has outwardly removable ends 4. The ends 4 may be made of an asbestos composition, or any other suitable refractory material.

An upper drum 5 is mounted in the ends of the 45 casing 1. A lower drum 6 is mounted in the ends 4 of the casing 1 and on the forward base wall 2. The drums 5 and 6 are cylindrical, and are disposed in vertical alinement, the drum 5 being above the drum 6. The drums 5 and 6 are supported at their sides, from the sides of the casing 1, by anchors 7, shown in Fig. 3. The anchors 7 may be in the form of baffles, as long as desired, and extended longitudinally of the casing 1. The 50 upper drum 5 has a downward and rearward inclination of about one to twelve. The lower drum 6 has a downward and forward inclination of about one to twelve. The inclination of the drums 5 and 6 aids in keeping the asphalt sand

moving, and because the drums are inclined, the heat is greatest at the lower end of each drum.

A square vertical pipe 8 is connected at its upper end to the lower end of the upper drum 5, the lower end of the pipe 8 being connected to the upper end of the lower drum 6. By means of the pipe 8, the material is conducted from the upper drum 5 to the lower drum 6. The flow of material through the pipe 8 is regulated by a horizontal gate 9, slidably mounted in the pipe 8. On its rear side, the pipe 8 has an opening 10, controlled by a closure 11, slidably mounted on the pipe. The opening 10 and the closure 11 are for the purpose of permitting samples to be taken out at any time.

The upper drum 5 has a forward head 12 and a rear head 14. The lower drum 6 has a forward head 15 and a rear head 16. All of the heads specified are removable, so as to give access to the drums. The end members 4 of the casing 1 also are removable, to give access to the space within the casing 1, about the drums 5 and 6. The construction is such that the interior of the machine can be got at readily, for the making of repairs and the like. In the heads 12 and 14 of the drum 5 there are holes 17, and in the head 15 of the drum 6 there is a hole 18. The holes 17 and 18 give access to the drums. Pipes 19 are secured detachably, if desired, to the heads 12 and 14 of the drum 5, about the openings 17. A similar pipe 20 is secured to the head 15 of the drum 6, about the opening 18. The vapors produced during the operation of the machine are taken off through the pipes 19 and 20. At its top and near to its forward end, the upper drum 5 has an outwardly extended oil inlet pipe 21. At its top, and adjacent to its rear end, the upper drum 5 is provided with an outwardly extended asphalt inlet pipe 22. The head 16 of the drum 6 is supplied in its upper portion with an oil inlet pipe 23 and with an asphalt inlet pipe 24. The heater for the casing 1 is shown at 25 and may be mounted in the base wall 3. The showing of the drawings respecting the heater 25 is diagrammatic, and any form of heater or burner may be employed.

The heads 12 and 14 of the upper drum 5, and the heads 15 and 16 of the lower drum 6, carry external bearings 26. In these bearings are journaled the cylindrical ends of square shafts 27. The cylindrical ends of the shafts 27 are marked by the numeral 28. On the rear end of each shaft 27, that is, on the rear cylindrical portion 28 thereof, there is secured a gear wheel 29. The gear wheels 29 mesh with pinions 30 on the shafts 35

of electrical motors 31. The motors 31 may be supported in any suitable way, for instance, but not of necessity, as shown at 32. Each of the motors 31 is so constructed that it can be run at three different speeds. Arranged in a spiral around each shaft 27 are paddles 33. The outer ends of the paddles 33 are set at an acute angle to the axis of the shaft 27 that carries them. The shafts 27 are located a little below the axis 5 of the respective drums 5 and 6. The result is that the outer ends of the paddles will scrape, or run extremely close to the lower third of each of the drums 5 and 6, considered circumferentially, the outer ends of the paddles moving clear of the 10 upper portion of each drum, as Fig. 3 will show. A proper advancement and agitation of the material thus is secured, and power is saved, because the outer ends of the paddles do not scrape on the drums throughout the entire 15 circumference of the drums. The material in the lower third (or thereabout) of each of the drums 5 and 6 is scraped clear of the drum.

The numeral 34 marks a hopper, located at the forward end of the casing 1 and a little to 20 one side of the casing. The hopper 34 has a tapered lower end 35. The hopper 34 may be supported by any suitable means, indicated generally at 36. The hopper 34 has a circumscribing jacket 37. A pipe 38 leads from the casing 1 to the jacket 37. The jacket 37 has an outlet 39, located wherever desired. The purpose of the jacket 37 is to drive out the moisture in the asphalt sand that is in the hopper 34 and to prevent caking. By means of the pipe 38, the 25 jacket 37 and the outlet 39, the waste heat from the casing 1 is utilized, and the casing is given an outlet for the products of combustion from the burner 25 or its equivalent.

At its lower end, the part 35 of the hopper 34 30 discharges into, and is connected to an inclined chute 40, which may be in the form of a trough. A short L-shaped pipe 41 connects the inner end of the chute 40 with the upper drum 5, through the drum head 12. A burner 42 is disposed 35 lengthwise of the chute 40, underneath the chute. The burner 42 is supported at 43 from the chute 40, if desired, and its purpose is to heat the material moving along the chute and to drive out any moisture that may happen to remain in the material. The material is advanced along the chute 40 by a worm conveyor 44. The worm conveyor 44 40 is secured to a shaft 45 journaled in the chute and in a bearing 46 carried by the tapered lower end 35 of the hopper 34. Rotation is imparted to the shaft 45 by any suitable instrumentality, such as a motor 47 carried by the part 35 of the 45 hopper 34 and connected operatively with the shaft 45 through gearing 48. Some may prefer to drive the shaft 45 in a different way, and that is permissible.

In the lower forward portion of the drum 6 there is outlet opening 49. A depending tubular skirt 50 on the drum 6 surrounds the opening 49 and prevents air from drawing into the opening 49 to an undesirable extent. The lower end of the skirt 50 is disposed close to a short, power driven belt conveyor 51 extended longitudinally of the machine. The material discharged by the belt conveyor 51 drops on a screen 52, which may be constructed as desired. Having passed through the screen or grate 52, the material is carried away by a power driven, transverse belt conveyor 53. The belt conveyor 53 sometimes is made of a rubber compound, and to prevent the granulated material from sticking to the belt conveyor, a 55

spray of fine, cold water is discharged downwardly on the said belt conveyor, through a spray head 54, the granulated mica asphalt being cooled, and being prevented from adhering to the conveyor 53, as aforesaid.

In practical operation, the machine is used for the purpose of tempering asphalt rock and petroleum asphalt, and for fusing a binder with them, to make a superior grade of mica asphalt.

The material to be tempered is introduced into the hopper 34, and in the hopper, most of the moisture is driven off, by the action of the jacket 37, which derives its heat from the casing 1, by way of the pipe 38, the products of combustion leaving by way of the outlet 39. In practical 10 operation, the material flows from the tapered lower end 35 of the hopper 34 into the outer end of the chute 40. The material here is engaged by the worm conveyor 44, driven from the motor 47, and is advanced lengthwise of the chute 40. 15 Whilst the material is being advanced in the chute 40, any moisture content that may be remaining in the material is driven off by the burner or heater 42 that is located below the chute 40. The material enters the upper drum 5, through the 20 pipe 41.

In the upper drum 5, the material is advanced, owing to the inclination of the drum 5, and owing to the action of the paddles 33, the paddles, of course, agitating the material. The petroleum 25 asphalt is added to the material in the drum 5, by way of the pipe 22.

The material passes downwardly through the pipe 8, into the drum 6, the flow of material through the pipe 8 being governed by the gate 9, 30 and it being possible to sample the material at this point, by opening the closure 11.

The material proceeds downwardly along the drum 6, owing to the inclination of the drum, and to the action of the paddles 33 in the drum 6, the 40 paddles of both drums being driven from the motors 31 by way of the gearing shown at 30-29, and through the instrumentality of the shafts 27. The material, at a temperature approaching 1000 degrees Fahrenheit, produced by the heating 45 means shown at 25, leaves by way of the outlet 49 and the skirt 50, the material being carried away by the belt conveyor 51 and the belt conveyor 53, the material being cooled, before it reaches the belt conveyor 53, by the water spray 50 discharged from the means shown at 54.

As the material passes through the drums 5, longitudinally thereof, the difference in temperature at the opposite ends of the two drums makes it possible to vaporize everything in the material or asphalt sand, from light to heavy oils, the vapors being taken off by the pipes 20 and 19. In case of emergency, when the rotation of the 55 shafts 27 may have been interrupted, the drums 5 and 6 can be flooded with crude oil, through the pipes 23 and 21, thereby preventing the material from caking on the drums.

The machine is so constructed that time and fuel are saved. The operation of the machine is continuous. The machine is equipped with constant feeding and discharging mechanisms. The speed of operation may be regulated by changing the speed at which the motors 31 operate, those motors, preferably, being three speed motors, as has been explained hereinbefore.

Having thus described the invention, what is claimed is:

1. In a machine for treating material of the class described, a casing, oppositely inclined upper and lower drums fixed in the casing, a mem- 75

ber establishing communication between the lower end of the upper drum and the upper end of the lower drum, an inlet for the material to be treated, discharging into the upper end of the upper drum, the lower end of the lower drum being provided with an outlet for the treated material, a combined conveyor and agitator in each drum and operating longitudinally thereof, means for heating the interior of the casing, about the drums, and a gate in said member, under the control of an operator, the gate regulating the amount of material that passes from the upper drum to the lower drum.

2. In a machine for treating material of the class described, a casing, oppositely inclined upper and lower drums fixed in the casing, a member establishing communication between the lower end of the upper drum and the upper end of the lower drum, an inlet for the material to be treated, discharging into the upper end of the upper drum, the lower end of the lower drum being provided with an outlet for the treated material, a combined conveyor and agitator in each drum and operating longitudinally thereof, means for heating the interior of the casing, about the drums, said member having an external sampling opening, and a movable closure for said opening.

3. In a machine for treating material of the class described, a casing, oppositely inclined upper and lower drums fixed in the casing, a member establishing communication between the lower end of the upper drum and the upper end of the lower drum, an inlet for the material to be treated, discharging into the upper end of the upper drum, the lower end of the lower drum being provided with an outlet for the treated material, a combined conveyor and agitator in each drum and operating longitudinally thereof, means for heating the interior of the casing, about the drums, said member being provided with an external sampling opening, a movable closure for said opening, and a gate in said member, and under the control of an operator, the gate constituting means for regulating the amount of material that passes from the upper drum to the lower drum.

4. In a machine for treating material of the class described, a casing, oppositely inclined upper and lower drums fixed in the casing, a member establishing communication between the lower end of the upper drum and the upper end of the lower drum, an inlet for the material to be treated, discharging into the upper end of the upper drum, the lower end of the lower drum being provided with an outlet for the treated material, a combined conveyor and agitator in each drum and operating longitudinally thereof, means for heating the interior of the casing, about the drums, the inlet for the material to be treated comprising a hopper, a heater for the contents of the hopper, and a conduit leading from the interior of the casing to the heater.

5. In a machine for treating material of the class described, a casing, oppositely inclined upper and lower drums fixed in the casing, a member establishing communication between the lower end of the upper drum and the upper end of the lower drum, an inlet for the material to be treated, discharging into the upper end of the upper drum, the lower end of the lower drum being provided with an outlet for the treated material, a combined conveyor and agitator in each drum and operating longitudinally thereof, means for heating the interior of the casing, about the drums, the inlet for the material to be treated comprising a hopper having an external jacket provided

with an outlet, and a conduit connecting the interior of the casing with the jacket, the means for heating the interior of the casing embodying a combustion device, and the products of combustion finding their way out of the casing, through the conduit, through the jacket, and through the outlet of the jacket.

6. In a machine for treating material of the class described, a casing, oppositely inclined upper and lower drums fixed in the casing, a member establishing communication between the lower end of the upper drum and the upper end of the lower drum, an inlet for the material to be treated, discharging into the upper end of the upper drum, the lower end of the lower drum being provided with an outlet for the treated material, a combined conveyor and agitator in each drum and operating longitudinally thereof, means for heating the interior of the casing, about the drums, the inlet for the material to be treated comprising a hopper and a chute leading from the hopper to the upper drum, a conveyor operating in the chute, and means for driving the conveyor.

7. In a machine for treating material of the class described, a casing, oppositely inclined upper and lower drums fixed in the casing, a member establishing communication between the lower end of the upper drum and the upper end of the lower drum, an inlet for the material to be treated, discharging into the upper end of the upper drum, the lower end of the lower drum being provided with an outlet for the treated material, a combined conveyor and agitator in each drum and operating longitudinally thereof, means for heating the interior of the casing, about the drums, the inlet for the material to be treated comprising a hopper, a chute leading from the hopper to the upper drum, a conveyor operating in the chute, means for operating the conveyor, and a heater extending longitudinally of the chute in heating relation thereto.

8. In a machine for treating material of the class described, a casing, oppositely inclined upper and lower drums fixed in the casing, a member establishing communication between the lower end of the upper drum and the upper end of the lower drum, an inlet for the material to be treated, discharging into the upper end of the upper drum, the lower end of the lower drum being provided with an outlet for the treated material, a combined conveyor and agitator in each drum and operating longitudinally thereof, means for heating the interior of the casing, about the drums, a first conveyor whereon the outlet for the treated material discharges, a second conveyor whereon the first conveyor discharges, a gate interposed between the conveyors, and means for cooling the treated material after it has passed the gate and is received on the second conveyor.

9. In a machine for treating material of the class described, a casing, oppositely inclined upper and lower drums fixed in the casing, a member establishing communication between the lower end of the upper drum and the upper end of the lower drum, an inlet for the material to be treated, discharging into the upper end of the upper drum, the lower end of the lower drum being provided with an outlet for the treated material, a combined conveyor and agitator in each drum and operating longitudinally thereof, means for heating the interior of the casing, about the drums, each combined conveyor and agitator embodying a shaft journaled in the drum, paddles carried by the shaft and cooperating with the

inner wall of the drum, and separate means for rotating each shaft at different speeds.

10. In a machine for treating material of the class described, a casing, oppositely inclined upper and lower drums fixed in the casing, a member establishing communication between the lower end of the upper drum and the upper end of the lower drum, an inlet for the material to be treated, discharging into the upper end of the upper drum, the lower end of the lower drum being provided with an outlet for the treated material, a combined conveyor and agitator in each drum and operating longitudinally thereof, means for heating the interior of the casing, about the drums, each combined conveyor and agitator embodying a shaft journaled in the drum, paddles carried by the shaft, and means for rotating the shafts, the shafts being so journaled that their axes are eccentric with respect to the axes of the drums, whereby the paddles will move close to the lower portions of the drums, and depart from the upper portions of the drums, as the shafts are rotated.
11. In a machine for treating material of the class described, a casing, oppositely inclined upper and lower drums fixed in the casing, a member establishing communication between the lower end of the upper drum and the upper end of the lower drum, an inlet for the material to be treated, discharging into the upper end of the upper drum, the lower end of the lower drum being provided with an outlet for the treated material, a combined conveyor and agitator in each drum and operating longitudinally thereof, means for heating the interior of the casing, about the drums, and the means for heating the interior of the casing, about the drums, embodying a burner located below the upper end of the lower drum and below the lower end of the upper drum.
12. In a machine for treating material of the class described, a casing, oppositely inclined upper and lower drums fixed in the casing, a member establishing communication between the lower end of the upper drum and the upper end of the lower drum, an inlet for the material to be treated, discharging into the upper end of the upper drum, the lower end of the lower drum being provided with an outlet for the treated material, a combined conveyor and agitator in each drum and operating longitudinally thereof, means for heating the interior of the casing, about the drums,

and each drum being provided with an outlet for the vapors created therein through the action of the means for heating the interior of the casing.

13. In a machine for treating material of the class described, a casing, oppositely inclined upper and lower drums fixed in the casing, a member establishing communication between the lower end of the upper drum and the upper end of the lower drum, an inlet for the material to be treated, discharging into the upper end of the upper drum, the lower end of the lower drum being provided with an outlet for the treated material, a combined conveyor and agitator in each drum and operating longitudinally thereof, means for heating the interior of the casing, about the drums, the upper drum being provided at both ends with an outlet for the vapor created in the drum by the action of the means for heating the interior of the casing, and the lower drum being provided at its lower end with a like outlet.

14. In a machine for treating material of the class described, a casing, oppositely inclined upper and lower drums fixed in the casing, a member establishing communication between the lower end of the upper drum and the upper end of the lower drum, an inlet for the material to be treated, discharging into the upper end of the upper drum, the lower end of the lower drum being provided with an outlet for the treated material, a combined conveyor and agitator in each drum and operating longitudinally thereof, means for heating the interior of the casing, about the drums, and each drum being provided with an inlet for oil, adapted to be used to flood the drum in emergency.

15. In a machine for treating material of the class described, a casing, oppositely inclined upper and lower drums fixed in the casing, a member establishing communication between the lower end of the upper drum and the upper end of the lower drum, an inlet for the material to be treated, discharging into the upper end of the upper drum, the lower end of the lower drum being provided with an outlet for the treated material, a combined conveyor and agitator in each drum and operating longitudinally thereof, means for heating the interior of the casing, about the drums, and means whereby petroleum asphalt is admitted to the upper drum.

JOSEPH ADELBERT WITHEE.
